UNITED STATES PATENT OFFICE.

ALFRED R. GILLHAM, OF CINCINNATI, OHIO.

PIANO-PLAYER.

1,390,697.

Application filed December 28, 1916. Serial No. 139,344.

Specification of Letters Patent. Patented Sept. 13, 1921.

To all whom it may concern:

Be it known that I, ALFRED R. GILLHAM, a citizen of the United States, residing at Cincinnati, in the county of Hamilton and 5 State of Ohio, have invented certain new and useful Improvements in Piano-Players, of which the following is a specification.

My invention relates to piano-players, and has for its object the provision of novel 10 means for accentuating the melody of the selection played, by automatically causing the piano-action units through which the melody is produced, to have a greater range of movement when actuated, than the range 15 of movement of the remaining units.

Further, it is the object of my invention to provide individual emphasizing means for the various piano-action units, so arranged that the emphasizing means coacting 20 with the piano-action units adapted to produce the same note in the different octaves may be collectively controlled, and also to provide means for selectively neutralizing the action of the emphasizing 25 means in certain octaves. By neutralizing I mean wholly or partially neutralizing, counteracting or negativating the action or effect of the emphasizing means, and the term neutralize wherever employed in the description 30 and claims is to be understood and interpreted with such meaning.

My invention also contemplates the provision of means whereby the intensity of the tone of all the notes may be modified 35 while still maintaining the relative prominence of the melody producing notes.

Other objects of my invention will appear from the following description and claims, and from the drawings, in which latter:

40 Figure 1 is a vertical section through a piano constructed in accordance with my invention.

Fig. 2 is a plan view of a piano with the top of the casing removed, and certain of 45 the parts omitted or broken away for the sake of clearness.

Fig. 3 is a vertical section on the line 3—3 of Fig. 1, with certain of the parts omitted or broken away.

50 Fig. 4 is an enlarged fragmentary vertical section through the emphasizing pneumatic supporting frame.

Fig. 5 is an enlarged vertical section on the line 5—5 of Fig. 3, with certain of the 55 parts omitted.

Fig. 6 is a transverse section on the line 6—6 of Fig. 5.

Fig. 7 is an enlarged front elevation of a notesheet and tracker.

Fig. 8 is a fragmentary vertical section 60 similar to Fig. 1, showing a modified form of my invention.

Fig. 9 is an enlarged fragmentary section through the key-board of a piano showing a detail thereof.

65 My invention is exemplified as applied to a pneumatic piano-player, and may be applied to piano-players of well-known or standard constructions, and for the purpose of illustration, the present embodiment of 70 my invention is shown in connection with a piano-player comprising a piano-casing 11, having the usual sounding-board 12, carried by beams 13 at the rear of the casing. A string-frame 14 for the usual set of strings 75 15 is also arranged on beams 13, the strings coöperating with the sounding-board in a well-known manner by bridges 16.

A set of piano-action units 20 is arranged 80 transversely of the casing 11, preferably in the upper portion thereof in front of the string-frame, each unit having a hammer 21 adapted to strike a string of the string-set in the usual manner. A set of usual operating pneumatics for the piano-action units, is 85 shown at 26 arranged transversely of the piano-casing beneath the piano-action units, each operating pneumatic having an arm 27 arranged to engage a rod 28 having a positioning link 30 pivoted thereto and connected with the wippen 29 of the corresponding piano-action unit 20, to actuate the unit in a well-known manner.

90 The operating pneumatics are shown as upon supports 31 extending outwardly from a usual secondary valve-box 32, connected with a primary valve-box 33. The primary valve-box is connected by tubes 34 with the usual set of apertures 35 in a tracker 36, mounted within the usual casing 37 in the 100 front of the piano-casing. A take-up spool 38, and bearings 39 for a music-roll, are arranged within the casing 37 so that a perforated note-sheet 40 may be drawn over the tracker in the well-known manner. The 105 take-up spool is adapted to be actuated in the usual manner through a suitable gearing and pneumatic motor not shown.

110 The valve-boxes are preferably connected by ducts 45 and regulators 46 with a wind-

trunk 47, connected to which is a storer 48. A pair of bellows 49 is arranged on the wind-trunk, each of which are adapted to be operated by a treadle 50 through a suitable actuating arm 51. The treadles are preferably pivoted to a frame 52 adapted to swing out in front of the piano-casing, to bring the treadles into operative position in a well-known manner. The usual ledge 53 is preferably arranged at the front of the instrument to carry the operating keys and levers.

The parts as thus far described are of well-known construction and are illustrated and described in order that the relation of my improved device thereto may be readily understood, and it is therefore obvious that any preferred construction of pneumatic actuating mechanism for piano-players may be substituted for the construction as thus far described.

Individual emphasizing pneumatics are adapted to coact with the various piano-action units, to accentuate the melody of the selection to be played. In the present exemplification of my invention, the emphasizing pneumatics for the various piano-action units are shown supported within a frame 55 arranged to be moved relative to the set of piano-action units as desired, by mechanism to be hereinafter described. (See Figs. 1, 2, 3, 4 and 5.) The frame 55 is exemplified as comprising strips 56 extending transversely of the piano-casing in front of the piano-action units, and connected by end-pieces 57, the frame being slidably mounted upon the walls of the piano-casing, preferably by forming lugs 58 upon the end-pieces, adapted to be received in guideways 59 upon the piano-casing.

The pneumatics supported by frame 55 are preferably arranged between series of ducts formed at each side of the frame parallel to strips 56. This construction is exemplified as comprising a wall 68 spaced from each of the walls 56, the walls 68 extending the length of the frame 55, and supporting the pneumatics within a space 65 between the same. The series of ducts at each side of the frame are formed between the spaced walls 56 and 68, preferably by arranging partitioning-walls 63 in superposed spaced relation between the walls 56 and 68, side flanges 64 being formed upon the walls 56 and 68, and upon the partitioning-walls, so that the flanges form the sides of the ducts and the end-pieces 57 form the end walls thereof. (See Figs. 3, 5 and 10.)

The duct proximate to each of the walls 68 is preferably of substantially greater cross-sectional area than the remaining ducts 62, and is divided into a series of passage-ways 66, by transverse partitions 67, for a purpose to be hereinafter described.

65 The set of emphasizing pneumatics co-

operating with the various piano-action units, is preferably arranged within the space 65 with the individual pneumatics 72 disposed in opposed series extending the length of space 65, and supported upon the opposite walls 68. The individual pneumatics adapted to coöperate with the piano-action units for each octave, are preferably equally divided between the opposed series, with the pneumatics for an octave which are 75 in one series, opposite the pneumatics for the same octave which are in the opposed series. The passage-ways 66 are preferably so arranged relative to the pneumatics supported upon the wall 68 proximate thereto, 80 that a passage-way will be formed for each of the groups of pneumatics coöperating with piano-action units for the same octave.

The individual emphasizing pneumatics may be of any well-known type, and for the purpose of illustration are exemplified as comprising a stationary member 74, and a movable member 75 connected therewith in the usual manner by a flexible connection, so as to form a bellows 76. (See Figs. 4 and 90 5.) Means are preferably provided for normally holding the bellows in extended position, shown as comprising a spring 71 positioned between the stationary and movable members 74, 75, of the pneumatic. 95

Chambers 77, 78, between which are mounted a usual diaphragm 80, are formed in the stationary member, the chamber 77 being adapted to communicate through a port 79 with a connection leading to the tracker 36, and chamber 78 at the other side of the diaphragm communicating through port 81 with a connection leading to the wind-trunk 47. A valve-chamber 82 adapted to communicate with the chamber 78 is 105 provided with a usual double-faced valve 83 to control an opening 85 to the atmosphere, and a duct 86 leading to a port 87, through which communication is had with the interior of the bellows.

When the connection between the tracker and port 79 is closed to the atmosphere by a note-sheet passing across the tracker, suction is created through port 81 by the vacuum in the wind-trunk, which seats the valve 115 83 so as to cut off communication between duct 86 and chamber 78, and open duct 86 to the opening 85, admitting air at atmospheric pressure to the bellows, to extend the same as will be readily understood. 120

As soon as an opening in the note-sheet registers with the tracker opening for the connection leading from port 79 to the tracker, diaphragm 80 will be extended in a well-known manner, to actuate valve 83 125 so as to close the opening 85, and open duct 86 to chamber 78, the suction through chamber 78 and port 81 thus exhausting the air from the bellows and collapsing the same, in the usual manner. 130

The ports 81 in the stationary members of the pneumatics, are arranged to communicate with the wind-trunk 47 through the respective passage-ways 66 provided for 5 the various groups of pneumatics. This is preferably accomplished by forming each port 81 in the face 93 of the stationary member which abuts against wall 68, and forming a port 92 in the wall 68, in alinement

10 with each of the ports 81 of the pneumatics supported upon the wall, so that direct communication is provided between the ports 81 and their respective passage-ways 66.

15 The passage-ways 66 at opposite sides of the set of emphasizing pneumatics, which respectively communicate with the opposed groups of pneumatics coöperating with piano-action units for one octave, are adapted 20 to be connected with each other and with the wind-trunk by a conduit, instanced as a flexible tubing 95. For this purpose the passage-ways 66 to be connected, are provided with ports 94 respectively, and the 25 flexible tubing 95 is adapted to be connected to the wind-trunk 47 and to nipples 96 extending outwardly from said ports. The tubes 95 leading to the wind-trunk are preferably arranged in substantially parallel relation proximate to each other in front of 30 the frame 55, as shown at 100.

In order to provide a compact arrangement of the pneumatics 72 supported in opposed series within the space 65, the swinging end of the movable member of each pneumatics, is preferably of reduced width 35 as shown at 73 (see Fig. 3), so that the opposed pneumatics may have their ends disposed in staggered relation, thereby permitting 40 the swinging ends of the movable members of the respective pneumatics, to extend to the desired position in front of the respective piano-action units with which they coöperate.

45 The range of movement of hammer 21 of each of the piano-action units is adapted to be normally limited by the coöperating emphasizing pneumatic 72. This is preferably accomplished by securing an arm 91 to the 50 swinging end of the emphasizing pneumatic, the parts being so arranged that when the pneumatic is in its extended or normal position, the arm 91 supported thereby will form a stop for the hammer 21 before it reaches its 55 full inactive position, and thus prevent the full throw of the hammer when the piano-action unit is subsequently actuated by its operating pneumatic 26. When the pneumatic 72 is collapsed, the arm 91 is retracted 60 ed, thus permitting the hammer 21 to assume its full inactive position, and therefore, when subsequently actuated by its operating pneumatic, it will have its full range of movement for the purpose of producing 65 a tone of maximum intensity.

A pneumatic 72 is preferably provided for each action unit of the piano, although if desired, only the notes of a portion of the piano, preferably the middle range, may be arranged to be emphasized, by either only 70 providing a pneumatic for such notes, or only connecting the pneumatics of such notes with the mechanism for operating the pneumatics.

The mechanism for selectively collapsing 75 the pneumatics 72 as desired, so as to emphasize the notes controlled thereby, will now be described. The pneumatics coöperating with the various piano-action units producing the same note in the different octaves, 80 or as many thereof as desired, are so connected as to be simultaneously collapsed. In the present exemplification of my invention this is accomplished by providing a duct 62, for each of the notes in an octave, and 85 preferably arranging half of said ducts in each of the series at opposite sides of the set of emphasizing pneumatics.

The ports 79 of the pneumatics coöperating with piano-action units producing the 90 same note in the different octaves, are adapted to be connected to the duct provided for the particular note. This is preferably accomplished by forming a port 97 in the side of the duct in alinement with each of the 95 ports 79 with which the duct is to be connected. The respective pairs of ports 79 and 97 are then connected, preferably by a flexible conduit 99 received over nipples 98 extending outwardly from the ports 79 and 100 97 respectively.

The admission of air to ducts 62 is preferably controlled by the note-sheet 40 co-acting with the tracker 36. This is accomplished by forming an opening 104 in the 105 tracker-range for each duct 62. These openings are preferably provided in addition to the usual set of openings 35 to which the tubes 34 from the operating pneumatics are connected, but if desired, the number of 110 openings 35 may be reduced so as to provide a space for the openings 104 without increasing the width of the tracker-range. By the latter construction a piano-player of correspondingly reduced range will of course 115 be formed. The openings 104 are connected with their respective ducts 62, preferably by a flexible tube 105, fitting over nipples 106 extending outwardly from the respective openings 104 and ports 107 in the respective 120 ducts. The tubes 105 are preferably so arranged as to permit the frame 55 to freely slide in guideways 59 relative to the tracker.

By the construction as thus far described, admission of air through an opening 104 is 125 adapted to collapse all the emphasizing pneumatics connected to coöperate with the same note in the different octaves. Additional means are provided, however for selectively neutralizing the effect of the ad- 130

mission of air to certain of the emphasizing pneumatics thus connected, so that the note will only be emphasized in the octaves desired. In the present exemplification of my 5 invention this is accomplished by providing means for obstructing or cutting off communication between the wind-trunk and the respective tubes 95 connected with the exhaust ports 81 of the pneumatics coöperating with 10 the piano-action units of one octave.

The mechanism for selectively cutting off the respective tubes 95, is preferably pneumatically actuated, and is exemplified as comprising a back-plate 109 arranged in rear 15 of the tubes of the parallel series 100, and against which each tube is adapted to be pressed to close the passage therethrough. (See Figs. 3, 5 and 6.) The back-plate 109 is preferably provided at each end with an 20 attaching plate 110. The attaching plates are preferably adapted to be secured to a bracket 116 depending from a side wall of the series of ducts 62, by bolts 111. Brackets 112 extend outwardly from each attaching 25 plate 110, and are provided with alined openings in which are supported the respective ends of a shaft 114 extending transversely of tubes 95 in front thereof. A cam 115 is journaled upon shaft 114 in position 30 to coact with each of the tubes 95, and so arranged that partial rotation of a cam will press the flexible tube 95 with which it coacts against the back-plate 109, and thus choke or close the opening through the tube. 35 Each of the cams 115 is adapted to be actuated by a pneumatic 120, preferably of similar construction to the operating pneumatics 26, and having an arm 121 articulated with a lever 122 secured to the cam, 40 so that longitudinal movement of the arm will rock the cam. (See Figs. 1, 3, 5 and 6.) The pneumatics 120 are shown as mounted upon supports 123 extending outwardly from the secondary valve-box 32, which is 45 connected with the primary valve-box 33 within the piano-casing. A tube 124 for each of the pneumatics 120, is connected with the primary valve-box, and is arranged to lead to an opening 125 in the tracker 36, 50 so that the pneumatics 120 will be controlled by admission of air through their respective tracker openings 125. The tube 124 may have connection with the cracker through a nipple 106. 55 The admission of air to openings 125 is controlled by the note-sheet 40 in the usual manner, the openings 125 being preferably provided in addition to the usual set of openings 35 and the set of openings 104, 60 but if desired, the number of openings 35 may be reduced by providing a piano-player of correspondingly reduced range, so as to provide a space for the openings 125 without increasing the width of the tracker 65 range.

The pneumatics 120 may also be manually controlled. This is preferably accomplished by leading a branch tube 127 from each tube 124 to a position beneath the ledge 53 carrying the usual control levers for the piano. (See Figs. 1, 2 and 9.) Each tube 127 is provided with a normally closed valve 128, which is adapted to be opened, so as to admit air to the tube and the pneumatic 120 connected therewith, by a manually operated key 129 mounted upon the ledge 53.

By the construction as thus exemplified, it will be seen that while the admission of air through an opening 104 will normally collapse all the pneumatics 72 connected to co-operate with the same note in the different octaves, by admission of air to desired ones of the tubes 124 prior thereto, the wind-trunk 47 will be obstructed or cut off from all the emphasizing pneumatics coöperating 85 with piano-action units of the octaves controlled respectively by said tubes. Thus, only desired ones of the emphasizing pneumatics coöperating with the same note in different octaves will be actuated, to allow 90 the piano-action units controlled thereby to have a full throw when subsequently operated by their respective operating pneumatics 26.

In a piano-player constructed in accordance with my invention, and adapted to actuate all the notes of a piano of full range, comprising seven complete octaves and four additional notes, there will preferably be seven of the tubes 95, a tube being provided 100 for each complete octave with the pneumatics coöperating with the four additional notes connected with passage-way 66 and tube 95 of the adjacent complete octave. If it is desired to provide means for neutralizing the effect in each octave, of the admission of air through an opening 104, a cut-off 115 and a pneumatic 120 and its connections, will be provided for each tube 95. If in practice however, it is found desirable 110 to only control the middle range of the piano, a pneumatic 120 and its connections, and a cut-off valve 115, will only be provided for the octaves of the middle range.

The intensity of the tone of all the notes 115 of the piano is adapted to be modified as desired, while still maintaining the relative prominence of the melody. This is exemplified as accomplished by selectively operating the pneumatics 72, so as to increase the 120 range of movement of the desired piano-action units relative to the remaining units, as previously described, but also moving the frame 55 carrying the emphasizing pneumatics relative to the piano-action units, so 125 that all the notes will be modified as desired.

This is exemplified as accomplished by connecting the frame 55 which is mounted to slide in guideways 59, with a manually 130

operated key 134 arranged upon ledge 53 of the key-board. (See Figs. 1, 2 and 3.) The connection between frame 55 and key 134 is shown as comprising an arm 131 secured to 5 each end of the frame, each arm being articulated with a lever 132 secured to a rock-shaft 133 extending transversely of the piano-casing. Key 134 is adapted to actuate a lever 135 secured to said rock shaft 133, 10 by means of a lever 136 and a link 137. The parts are so arranged that when key 134 is raised or lowered, shaft 133 will be rocked to slide frame 55 relative to the piano-action units as desired. 15 In the modification of my invention illustrated in Fig. 8, the emphasizing pneumatics are adapted to coöperate with the piano-action units, by coacting with the rods 28' of the operating pneumatics 26', the rods 28' 20 being connected with the wippens 29' of the respective units as previously described.

In this construction, the frame 55' supporting the emphasizing pneumatics, is mounted below the set of operating pneumatic 26', and the pneumatics 72' supported thereby, are preferably so arranged upon walls 68' of parallel series of passage-ways 66' and ducts 62' carried by said frame, that the arms 91' supported by the 25 movable members 75' of the emphasizing pneumatics, will extend parallel to the rods 28', with each arm proximate to the rod with which it is adapted to coöperate. 30

The range of movement of each rod 28' 35 is adapted to be controlled by the coöperating arm 91', exemplified as accomplished by forming a shoulder 138 upon the rod 28' against which arm 91' is adapted to abut, the parts being so arranged that when an 40 emphasizing pneumatic is in its normal extended position, the arm 91' thereof will abut against shoulder 138 so as to limit the range of movement of the action unit by raising said rod 28' as indicated by the space 45 25' between said rod and the arm 27'. (See Fig. 8.)

Pneumatics 72' are preferably normally held in extended position by spring 71' between the stationary and movable members 50 74', 75', of each pneumatic.

When pneumatic 72' is collapsed, the vacuum in the wind-trunk overcoming the action of spring 71', its arm 91' will be retracted, so that rod 28' may assume its 55 full inactive position, and thus when subsequently actuated by arm 27' of the operating pneumatic engaging therewith, it will have its full range of movement to produce a tone of maximum intensity.

60 The pneumatics 72' are arranged to be controlled as described for pneumatics 72, and for this purpose are provided with conduits 99' connecting the pneumatic with their respective ducts 62', tubes 105' leading 65 from ducts 62' to the tracker, a series 100'

of tubes connecting the wind-trunk with passage-ways 66', and means as previously described for closing the tubes of series 100', comprising cams 115' mounted upon shaft 114' and to which are secured levers 70 122' articulated with arms 121'.

Pneumatics 120' are adapted to actuate the arms 121' and are shown as mounted upon supports 123' suitably secured to the secondary valve-box 32'. A tube 124' for 75 each of the pneumatics 120' leads to the tracker from the primary valve-box 33', and is also provided with manually controlled operating means comprising a valve 128' and key 129' arranged as previously described.

The frame 55' which may be suitably counterbalanced is adapted to be moved relative to the rods 28', so as to modify the tone of all the notes, and for this purpose the 85 end-pieces 57' of the frame are provided with lugs adapted to slide in guide-ways 59', suitably arranged upon the walls of the piano-casing, so that when the frame is moved therein, all the rods 28' will be correspondingly raised or lowered. This movement of the frame is manually controlled as previously described, by means of rock-shaft 133', actuated by key 134' positioned upon ledge 53' of the key-board so as 90 to be manually operated, the shaft 133' being connected with each end of the frame 55' by levers 132' secured to the shaft, and adapted to reciprocate arms 131' through suitable levers, arms 131' being secured to 100 the respective ends of the frame as previously described.

A note-sheet 40 adapted to be employed in connection with a piano-player constructed in accordance with my invention, is shown 105 in detail in Fig. 7, in connection with a tracker 36, the arrow showing the direction of its movement. The openings 125 for the neutralizing pneumatics 120, are shown as arranged at one end of the tracker, and as 110 being four in number, to control four octaves of the middle range of the piano, although as previously explained an opening 125 and pneumatic 120 may be provided for each octave of the piano, if desired. The 115 openings 104 for the emphasizing pneumatics 72, are shown as arranged next to the openings 125, and will be twelve in number, so that each of the twelve notes of an octave may be emphasized. The openings 35 for the 120 operating pneumatics 26 of the piano-player are preferably arranged next to the openings 104, and in a piano-player of full range will be eighty-eight in number, an operating pneumatic being provided for each note of 125 the standard piano.

The note-sheet 40 is provided with a column for each of the openings in the tracker-range, in each of which perforations are adapted to be formed to register with the co- 130

operating openings in the tracker. The perforations in the note-sheet arranged to co-operate with the set of openings 35 in the usual manner, to actuate the desired piano-action units, are shown at 142. When it is desired to emphasize notes caused to be played by the registering of the proper openings 35 and perforations 142 suitably formed in the note-sheet, perforations 143 are formed 10 in the note-sheet so as to register with openings 104 in the tracker, controlling the notes in the different octaves which it is desired to emphasize.

Thus for example, if it is desired to emphasize the note played by the registering of the perforation shown at 144 with its co-operating opening 35, a perforation will be formed in the note-sheet, so as to register with the opening 104 in the tracker controlling the note which it is desired to emphasize in the different octaves, as shown at 145. The perforation 145 is so arranged as to register with its tracker opening 104 slightly in advance of the registering of the perforation 144 with its opening 35, and is of sufficient length to remain in registering position until the piano-action unit has been actuated by the registering of perforation 144 and its opening 35.

By this arrangement the registering of perforation 145 with its tracker opening 104, will cause the collapse of all the emphasizing pneumatics 72 arranged to control the same note in different octaves, which are connected with the opening 104, and the piano-action units for this note in the different octaves will move to full inactive position so as to be capable of subsequently imparting a full blow to their respective strings. The registering of perforation 144 and its opening 35 will now actuate the desired one of the action units of the group thus having a full range of movement, to emphasize the note played thereby, the remaining ones of the units having full range of movement remaining idle. Upon a subsequent closing of the opening 104 by the note-sheet the collapsed pneumatics will return to normal position so as to reduce the range of movement 50 of the action units controlled thereby.

If it is desired to emphasize the note controlled by perforation 144, and at the same time emphasize a different note controlled by perforation 148, and played simultaneously, a perforation 149, in addition to perforation 145, will be formed in the note-sheet, so arranged as to register with the proper tracker opening 104 controlling the note in the different octaves, which it is desired to emphasize. Thus as many different notes as is desired may be simultaneously emphasized.

If it is desired to simultaneously play the same note in different octaves, and emphasize the note in certain of these octaves only,

perforations 142 are arranged as shown at 151, to simultaneously register with openings 35 by means of which the same note is adapted to be played in different octaves, and a perforation is so arranged in the note-sheet as to register with the tracker opening 104 controlling said note in the various octaves, as shown at 152 extending in advance of the perforations 151. By the construction as thus far described, the note to be 75 played, would be emphasized in all the octaves for which perforations 151 were provided.

In order to neutralize the effect of the registering of perforation 152 with its tracker opening 104, in the octaves for which perforations 151 are provided and in which it is not desired to emphasize the note thus controlled, all the emphasizing pneumatics coöperating with action units in such octaves, are cut off from the wind-trunk 47 by closing the proper tubes 95, slightly in advance of the registering of perforation 152 with its tracker opening 104.

Only the pneumatics connected with 90 tracker opening 104 controlled by perforation 152, and which are arranged to coöperate with notes in the octaves which are not cut off from the wind-trunk, will therefore be collapsed, to release the action units with 95 which they coöperate, so that the action units will be capable of imparting a full blow to the respective strings when subsequently actuated by the registering of perforations 151 with their openings 35. 100

The closing of the desired tubes 95, in advance of the registering of tracker opening 104 with perforation 152, may be manually controlled by actuating the keys 129 controlling the pneumatics 120 connected with 105 the tubes 95 which it is desired to close, slightly in advance of the registering of perforation 152 with its tracker opening.

The closing of the desired tubes 95, may also be automatically controlled by providing perforations 160 in the note-sheet, so arranged as to register with the tracker openings 125, controlling the pneumatics 120 connected with the tubes 95 which it is desired to close, slightly in advance of the registering of perforation 152 and its tracker opening 104. The perforations 160 are of 110 such a length as to remain in registering position with tracker openings 125 as long as the perforation 152 is in registering position with its tracker opening 104.

If it is desired to simultaneously play two or more notes, each note being played in a plurality of octaves, and emphasize the notes in certain octaves only, a plurality of sets of 125 perforations 142 for the same note in different octaves, are arranged in the note-sheet as shown at 165, 166, and perforations are so arranged in the note-sheet as to register previous to the registering of perforations 165, 130

166, with their respective openings 35, with each of the tracker openings 104 controlling the respective notes to be emphasized, as shown at 167, 168. The wind-trunk 47 is 5 previously cut off from all the octaves for which perforations 165, 166, are provided, except the octaves in which it is desired to emphasize the notes, by the mechanism controlled by a perforation such as shown at 10 169 and as previously described. By this arrangement, as many notes in as many octaves as desired, may be simultaneously played, the desired notes in certain octaves only being emphasized.

15 It will therefore be seen that I have provided a construction, whereby, by the employment of a note-sheet properly perforated, the desired notes of the selection played may be automatically emphasized to 20 accentuate the melody of the selection, and thus produce the effect of a manually played piano.

Having thus fully described my invention, what I claim as new and desire to secure by Letters Patent, is:

25 1. In a device of the character described, the combination with a set of piano-action units, of automatic means for selectively emphasizing the respective notes produced by 30 the action of said units, and means for regulating the intensity of sound of all of said notes while maintaining the relative prominence of the selectively emphasized notes.

35 2. In a device of the character described, the combination with a set of piano-action units and a note-sheet, of operating pneumatics coacting with said piano-action units, and emphasizing pneumatics, said note-sheet provided with perforations coacting with 40 said operating pneumatics and with separate perforations coöperating with said emphasizing pneumatics.

45 3. In a device of the character described, the combination with a set of piano-action units and a note-sheet, of operating pneumatics coacting with said piano-action units, and emphasizing pneumatics, said note-sheet provided with perforations coacting with 50 said operating pneumatics and with perforations coöperating with said emphasizing pneumatics, said last-named perforations in said note sheet extending in advance of said first-named perforations and affecting a plurality of notes.

55 4. In a device of the character described, the combination with a set of piano-action units and a note-sheet, of operating pneumatics coacting with said piano-action units, emphasizing means comprising emphasizing 60 pneumatics, pneumatic control passages therefor and neutralizing means acting on said pneumatic control passages, said note-sheet provided with perforations coacting with said operating pneumatics and with

perforations coacting with said emphasizing 65 pneumatics.

5. In a device of the character described, the combination with a set of piano-action units and a note-sheet, of operating pneumatics coacting with said piano-action units, 70 emphasizing means including emphasizing pneumatics, and neutralizing means for said emphasizing means including neutralizing pneumatics, said note-sheet provided with perforations coacting with said operating 75 pneumatics, with perforations coacting with said emphasizing pneumatics, and with perforations coacting with said neutralizing pneumatics.

6. In a device of the character described, 80 the combination with a set of piano-action units and a note-sheet, of operating pneumatics coacting with said piano-action units, emphasizing means including emphasizing pneumatics, and neutralizing means for said 85 emphasizing means including neutralizing pneumatics, said note-sheet provided with perforations coacting with said operating pneumatics, with perforations coacting with said emphasizing pneumatics, and with perforations coacting with said neutralizing pneumatics, said second-named perforations extending in advance of said first-named perforations.

90 7. In a device of the character described, 95 the combination with a set of piano-action units and a note-sheet, of operating pneumatics coacting with said piano-action units, emphasizing means including emphasizing pneumatics, and neutralizing means for said 100 emphasizing means including neutralizing pneumatics, said note-sheet provided with perforations coacting with said operating pneumatics, with perforations coacting with said emphasizing pneumatics, and with perforations coacting with said neutralizing pneumatics, said last-named perforations being in lateral line with said second-named 105 perforations, and said second-named perforations extending in advance of said first-named perforations.

110 8. In a device of the character described, the combination of a set of automatically operated piano-action units, emphasizing pneumatics arranged to coöperate with the respective action units, means for selectively actuating said emphasizing pneumatics to vary the range of movement of the respective action units, neutralizing means for 115 said last-named means comprising a neutralizing part, and means for moving said emphasizing pneumatics and said neutralizing part relative to said action units.

120 9. In a device of the character described, the combination of a set of pneumatically 125 operated piano-action units, a tracker, a wind-trunk, emphasizing pneumatics arranged to coöperate with the respective ac-

- tion units, connections between said tracker and the emphasizing pneumatics respectively coöperating with action units for notes of the same note name in different octaves, connections between said wind-trunk and the emphasizing pneumatics respectively coöperating with action units for notes of the same note name of given octaves, and means for selectively obstructing 10 the said last-named connections.
10. In a device of the character described, the combination of a set of pneumatically operated piano-action units, a tracker, a wind-trunk, emphasizing pneumatics for the 15 respective action units, connections between said tracker and said emphasizing pneumatics, connections between said wind-trunk and the emphasizing pneumatics respectively coöperating with action units for the 20 notes of given octaves, means for obstructing said last-named connections respectively, pneumatics respectively actuating said obstructing means, and connections between said tracker and said pneumatics.
25. 11. In a device of the character described, the combination of a set of pneumatically operated piano-action units, a tracker, a wind-trunk, emphasizing pneumatics for varying the range of movement of the 30 respective action units, connections between said tracker and said emphasizing pneumatics respectively coöperating with action units for notes of the same note name in different octaves, connections between said 35 wind-trunk and said emphasizing pneumatics respectively coöperating with action units for the notes of given octaves, neutralizing pneumatics for cutting off said last-named connections respectively, and 40 connections between said respective neutralizing pneumatics and said tracker.
12. In a device of the character described, the combination of a set of piano-action units, operating pneumatics, a tracker having 45 openings therein connected with the respective operating pneumatics, emphasizing pneumatics coöperating with said action units, said tracker having openings therein connected with the emphasizing pneumatics
- coöperating respectively with action units, 50 for notes of the same note name in different octaves, neutralizing pneumatics coöperating respectively with action units for the notes of an octave, said tracker having openings therein connected with said neutralizing pneumatics respectively, and a note-sheet 55 controlling said openings of said tracker.
13. In a device of the character described, the combination of a set of piano-action units, operating pneumatics, a tracker having 60 openings therein for the respective operating pneumatics, emphasizing pneumatics for said action units respectively, said tracker having openings therein respectively connected with emphasizing pneumatics for 65 action units for notes of the same note name in different octaves, neutralizing pneumatics for action units respectively for the notes of an octave, said tracker having openings 70 therein respectively connected with said neutralizing pneumatics, a note-sheet having 75 coöperating perforations therein arranged to successively register with openings of said tracker connected respectively with neutralizing, emphasizing and operating pneumatics. 75
14. In a device of the character described, the combination with a set of piano-action units and a note-sheet, of operating pneumatics coacting with said piano-action units, emphasizing means including emphasizing pneumatics, and neutralizing means for said 80 emphasizing means including neutralizing pneumatics, said note-sheet provided with perforations coacting with said neutralizing pneumatics, with perforations coacting with 85 said emphasizing pneumatics, and with perforations coacting with said operating pneumatics, said perforations extending in advance of one another in the sheet in the order named. 90
